UNITED STATES PATENT OFFICE.

THOMAS GLOVER, OF EDMONTON, LONDON, ENGLAND.

COIN-CONTROLLED MECHANISM.

1,367,371.

Specification of Letters Patent.

Patented Feb. 1, 1921.

Application filed October 24, 1919. Serial No. 332,973.

To all whom it may concern:

Be it known that I, THOMAS GLOVER, a subject of the King of Great Britain, residing at Edmonton, London, England, have 5 invented certain new and useful Improvements in Coin-Controlled Mechanism, of which the following is a specification.

This invention relates to that class of coin freed mechanism in which the coin carrier 10 is composed of two cups arranged on the operating shaft and slotted to receive the coin, one cup being fixed to the shaft while the other is loosely arranged thereon but connected by a train of wheels to the operating 15 mechanism the object being to positively lock the movable cup until the coin has been inserted in the carrier and the carrier moved a short distance, thus preventing any fraudulent tampering with the mechanism.

20 My invention will be described with reference to the accompanying drawings in which—

Figure 1 is a perspective view of the two 25 coin receiving cups having my invention applied thereto.

Fig. 2 is an end elevation.

For the purpose of my invention I make the two coin slots A in the loose cup B 30 wider than necessary to receive the coin and adjacent to these two slots or at any other part on the end wall of the cup I form recesses C. To some part of the casing I pivot a U or equivalent lever D one leg E being longer than the other and provided 35 with a lug or projection F which will engage either of the recesses C in the loose cup B, the other end G being angled or curved as at H and against which the coin 40 will act during its travel for the mechanism to be operated, so as to lift the other leg E and lift the lug or projection F from a recess C. The lever D is either positioned by gravity or by a spring.

45 In action the lever D is so positioned that the lug or projection F engages a recess C and the curved end H is in the path of the coin I. The loose cup B being in such position that one of the coin slots thereof coincides with the slot L in the cup J, when a 50 coin is inserted it will cause the two cups B, J to move together. The shaft K is now

rotated and the coin being held in the narrower slot L of the cup J, the edge of said coin acts upon the curved edge H of the member G of the U lever D and lifts the lever about its pivot pin M thus lifting the lug or projection F clear of the recess C. During this movement the coin has not caused the loose cup B to move by reason of the slot A in the cup B being wider than the slot L in the cup J and the coin having to travel across said wider slot before engaging the wall of the slot A. When the two cups B, J and coin I move together the coin I will leave the curved edge H of the U lever D and the lug F will ride on the edge of the cup. When the cups have been revolved their full distance the lug F will drop into the next recess C to hold the loose cup fast with the other slot positioned to receive a coin. The coin is then discharged and the other cup J may be rotated in the opposite direction so as to position its slot to coincide with a slot A in the cup B to receive a fresh coin.

N is the usual guide along which the coin travels before being discharged.

As will be understood the cup B is connected by suitable gear to the operating mechanism.

What I do claim as my invention and desire to secure by Letters Patent is:—

1. In a coin freed mechanism, a shaft, a pair of cups having coin receiving slots, one 85 of said cups being fixed to said shaft and the other being loosely mounted on said shaft, the slot of the latter cup being wider than that of the other cup, a U-shaped lever having one arm adapted to normally engage and secure said last-named cup against rotation with its slot coinciding with the slot in the other cup, said lever having its other arm engageable and actuated by a coin inserted in said slots when said first-named cup is rotated.

2. In a coin freed mechanism, a shaft, a pair of cups one provided with a coin-receiving slot and fixed to said shaft and the other loosely mounted on said shaft and having coin receiving slots wider than the slot in the other cup and also having a plurality of notches, a U-shaped lever having one arm provided with a lug adapted to

enter a notch in the last-named cup to secure said cup against rotation with one of its slots coinciding with the slot in the other cup, said lever having its other arm engageable by a coin inserted in the slots of said cups to lift the lug carried by said first-named arm from said notch in said cup.

In testimony whereof I have hereunto set my hand in presence of two subscribing witnesses.

THOMAS GLOVER.
